UNITED STATES PATENT OFFICE.

ERNST TERNSTRÖM, OF JEMEPE-SUR-MEISE, BELGIUM, ASSIGNOR OF ONE-HALF TO
SOCIÉTÉ ANONYME JOHN COCKERILL, OF SERAING, BELGIUM.

ARMORED CUPOLA.

1,188,702.

Specification of Letters Patent. Patented June 27, 1916.

Application filed April 18, 1914. Serial No. 832,850.

To all whom it may concern:

Be it known that I, ERNST TERNSTRÖM, a subject of the King of Sweden, residing at No. 62 Quai des Carmes, Jemeppe-sur-
5 Meise, Belgium, have invented new and useful Improvements in or Connected with
10 Armored Cupolas, of which the following is a specification.

This invention relates to armored cupolas and especially to the arrangement of the ports or embrasures in the hood through which the gun is fired.

Heretofore cupolas have been constructed wherein the port or embrasure has had formed around it on the inner side of the hood a hollow spherical bed, in which an obturator or gas check, on the barrel of the gun, formed with a corresponding spherical surface is fitted, such spherical surfaces 20 forming the pivot or joint upon which the training of the gun takes place.

Generally speaking the gas check upon the gun is sufficiently elastic to allow of a certain distortion of the spherical joint, such 25 as may be caused by a shot striking close to the port, without hindrance to the elevation of the gun, but even a slight distortion suffices to cause leakage around the gas check and a more pronounced distortion may render the working of the gun impossible.

The object of my present invention is to arrange the spherical joint and gas check, so that, notwithstanding that the hood may be injured locally or even displaced within certain limits, the laying of the gun and the tightness of the gas check will not be affected, and to this end my invention consists in arranging the gas check and the spherical joint entirely distinct from the hood.

According to my invention the spherical bed is formed as a separate part and is carried by the gun carriage or mounting, the said spherical bed being designed to enter a recess formed in the hood or cover around the embrasure or port, the said recess being, however, of larger diameter than the spherical bed, so as to leave a space sufficient to allow of a maximum distortion of the hood and other parts without injuring the 50 spherical bed.

In the accompanying drawing:—Figure 1 is a sectional elevation illustrating the application of my invention to a cupola, the hood or cap of which is of wrought steel. 55 Figs. 2 and 3 are respectively a side eleva-

tion and a plan of the spherical bed detached, and Fig. 4 is a plan view of part of a clip used in connection with this joint. Fig. 5 is a sectional elevation illustrating the application of my invention to a cupola having a cap or hood of cast steel and Figs. 6 and 7 are respectively a front view and a plan of the spherical bed of the joint detached.

In the arrangement of the invention shown in Figs. 1 to 3, *a* indicates the hood or cap *b* the port or embrasure therein and *c* the spherical bed of the joint which is shown detached in Figs. 2 and 3 and which is designed to be secured to the gun mounting *d*. 60 This spherical bed *c* which is of wrought metal is provided with a flange *e* which approximately corresponds with the internal surface of the hood around the embrasure, but in order to prevent gas from the muzzle 65 of a gun, or from a shell bursting close to the port *b* returning through the space *f* around the outside of the bed into the interior of the cupola, an annular packing *g* of elastic material is inserted between the hood and the flange *e*, as clearly shown in the drawings. As shown in Fig. 1, the said flange *e* is in the form of a ring which is 70 screwed on to the bed *c* and which serves to clamp the packing ring *g* against the interior of the hood *a*, the said packing ring being advantageously surrounded by a band or clip *h*, as shown in Figs. 1 and 2, and a part of which is shown detached in Fig. 4. 75

The arrangement shown in Figs. 5 to 7 is 80 constructed on the same principle as that hereinbefore described; in this case, however, the spherical bed *i* instead of being provided with an inclined flange to fit against the curved inner surface of the hood *a* is adapted to enter a vertical recess formed on the inside of the said hood, and is shown as forming part of the mounting *k* of the gun instead of being attached to the mounting as described in the previous arrangement. Also in this modification, the space 85 between the outside spherical bed and the adjacent surface of the hood is filled by the elastic packing *l* against which the ring *m* presses to hold the said packing in place. 100

Claims:

1. An armored cupola comprising a hood provided with a port, a gun mounting provided within said hood, a gun carried by said mounting and provided with an obtu- 110

rator having a spherical surface the axis of which is coaxial with that upon which the gun pivots in the mounting, a spherical bed provided upon said gun mounting with which the obturator engages, and an elastic packing arranged between said spherical bed and the adjacent surface of said hood around said port.

2. An armored cupola comprising a hood provided with a port, a gun mounting provided within said hood, a gun carried by said mounting and provided with an obturator having a spherical surface the axis of which is coaxial with that upon which the gun pivots in the mounting, a spherical bed provided upon said gun mounting with which the obturator engages, said spherical bed extending into said port but being out of contact with the wall of the same, and an elastic packing arranged between said spherical bed and the adjacent surface of said hood around said port.

3. An armored cupola comprising a dome-shaped hood provided with a port, a gun mounting provided within said hood, a gun carried by said mounting and provided with

an obturator having a spherical surface, the axis of which is coaxial with that upon which the gun pivots in the mounting, a spherical bed provided upon said gun mounting with which the obturator engages, a flange ring screwed upon the spherical bed, and a packing ring provided between said flange and the adjacent surface of said hood around said port.

4. An armored cupola comprising a dome-shaped hood provided with a port, a gun mounting within said hood, a gun carried by said mounting and provided with an obturator having a spherical surface, a spherical bed provided upon said gun mounting with which the obturator engages, said spherical bed extending into said port but being out of contact with the wall of the same, an adjustable ring provided upon said spherical bed, and a packing provided between said ring and the adjacent surface of said hood around said port.

ERNST TERNSTRÖM.
